UNITED STATES PATENT OFFICE.

JOHN E. GREENAWALT, OF DENVER, COLORADO, ASSIGNOR OF ONE-HALF
TO WILLIAM ROBINSON, OF DENVER, COLORADO.

OXIDIZING-FURNACE.

SPECIFICATION forming part of Letters Patent No. 717,093, dated December 30, 1902.

Application filed April 8, 1902. Serial No. 101,921. (No model.)

To all whom it may concern:

Be it known that I, JOHN E. GREENAWALT, a citizen of the United States of America, residing at Denver, in the county of Arapahoe and State of Colorado, have invented certain new and useful Improvements in Oxidizing-Furnaces; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in oxidizing-furnaces; and its object is the perfect and thorough oxidation of ores containing one or more valuable metals—such as gold, silver, or copper—as a necessary preliminary treatment to the successful extraction of these metals from refractory ores by means of chemical solutions. The roasting operation has an all-important bearing upon the subsequent recovery of the gold through 25 the medium of such solutions as chlorin and bromin. The consumption of these elements depends very largely upon the thoroughness and completeness of the oxidizing process. It is important that the sulfur be completely eliminated and that the iron be converted into the soft porous ferric oxid (Fe_2O_3) instead of the hard vitreous magnetic oxid, (Fe_3O_4), since the latter compound causes a large consumption of chlorin and large gold losses in the tailings.

30 My researches on this point have proven that when a burning particle of iron sulfid is completely surrounded by a highly-oxidizing atmosphere at not too high a temperature the iron will be completely converted into ferric oxid, whereas if the burning particle is in a reducing, neutral, or even slightly-oxidizing atmosphere the magnetic oxid is rapidly formed.

In my improved oxidizing-furnace the particles of ore fall through a strong oxidizing atmosphere at a sufficiently high temperature to start and maintain combustion until the combustible elements have been completely oxidized.

45 The furnace consists of five distinct parts—first, the hot-air compartments, where an

abundance of superheated air and steam is produced for the roasting-compartments; second, the roasting-compartments, where the ore particles are passed through the highly-oxidizing atmosphere; third, the dust-chamber, where the solid particles of ore are allowed to settle preparatory to returning them to the roasting-compartments; fourth, the acid-tower, where all the metallic fumes and intensely fine solid particles of ore are condensed and a dilute solution of sulfurous and sulfuric acid produced, and, fifth, the hot-ore pit.

Having thus briefly outlined the nature of the invention, the objects sought, and the main features of the mechanical construction, I will proceed to describe the same in detail, reference being made to the accompanying drawings, in which is illustrated an embodiment thereof.

In the drawings, Figure 1 is a vertical longitudinal section of the furnace, taken on the line xx , Fig. 2. Fig. 2 is a horizontal section taken on the line yy , Fig. 1. Fig. 3 is a vertical cross-section taken on the line zz , Fig. 2, viewed in the direction of the arrow. Fig. 4 is a vertical section taken on the line RR , Fig. 2, viewed in the direction of the arrow. Fig. 5 is a similar section taken on the line CD , Fig. 2. Fig. 6 is a section taken on the line AB , Fig. 2, viewed in the direction of the arrow. Fig. 7 is a section taken on the line DD , Fig. 1.

The same reference characters indicate the same parts in all the views.

Let the numeral 5 designate the hot-air compartments, which are two in number and of the same construction in every respect. Each of these compartments consists of a combustion-chamber or fire-box 5^a and a large space 5^c, filled with brick checker-work, in which the bricks are so arranged as to occupy about half the space. To the upper end of the stack portion of each of these chambers or compartments is fastened a truncated casting 5^j, provided with an orifice sufficiently large to carry away the gases from the fire when the checker-work is heating. Above this casting is a suitable lid or covering 6, which will be termed a "valve." One of these valves is constructed to accurately fit

into and close the opening in the top of each stack. Above the valves are wheels or pulleys 7, over which passes a flexible cable 8, to the ends of which are respectively fastened the two valves 6, so that by moving the cable the opening of one stack is opened, while the other is closed. The upper ends of these stacks are connected by means of suitable conduits 9 to a fan or blower 10. The lower portions of the hot-air compartments 5 are respectively connected with the adjacent roasting-compartments by means of flues 13. These two flues are controlled by a damper 14, which is adapted to open one and close the other. By moving this damper back and forth in a recess 15 one of the flues is closed and the other opened.

The ore-roasting part of the furnace preferably consists of three vertical shaft-compartments 16, 17, and 18. The bottom of the compartment 16, which I for convenience term the "first compartment," is connected with the top of the second compartment 17 by means of an iron chain or bucket elevator 19, which takes the hot and partially-roasted ore from the bottom of the compartment 16 and elevates it to the top of the compartment 17; also, the bottom of the compartment 17 is connected with the top of the compartment 18 by means of an elevator 20. The discharge-spout of the elevator 19 is connected with a suitable pipe 22 to carry the ore from the elevator to the compartment 17 by means of a screw conveyer 17^a, which spreads the ore and scatters it over the entire chamber, thus exposing each particle independently to the heated gases. In like manner the ore is discharged from the elevator 20 to the roasting-compartment 18 by a pipe 22^a and a conveyer 17^c. The completely-roasted ore finally falls upon the bottom of the compartment 18, where it mingles with the fine dust from a dust-chamber and together pass into the hot receiving-pit 45, having a hollow wall 46, supported in its lower portion and perforated to allow air under pressure to pass therethrough into the ore for cooling purposes. The bottom of this pit is provided with an opening 47 for the escape of the roasted ore. Below this opening is located an endless traveling chain 48, mounted upon wheels 49, for carrying the ore to the boot of an elevator 50, which carries it upwardly and discharges it through a spout 51 into an ore-bin or other suitable receptacle. (Not shown.) The top of the compartment 17 communicates with the top of a dust-flue 23, which conducts the furnace-gases into a dust-chamber 24. The lower part of the compartment 17 is connected with a supplemental combustion-chamber or firebox 25 by means of a flue 26. The object of this supplemental combustion-chamber is to bring the compartment 17 to the proper working temperature and in case of highly-silicious ores to assist in maintaining the temperature in this compartment.

The dust-receptacle 24 is a large chamber

where the velocity of the furnace-gases is reduced sufficiently to allow the solid particles to separate from the gases. This dust-chamber consists of two wings 24^b and 24^c. In the first wing 24^b the heavier particles fall to the chute 24^a and thence pass into one compartment 27^a of the conveyer-trough 27. The conveyer 27^c consists of two chains with flight attachments moving through the trough, the flights pushing the material through the trough. The ore particles in the compartment 27^a of the conveyer-trough are conveyed to an opening 27^d. (Indicated by dotted lines in Fig. 1, but not otherwise shown.) These ore particles are discharged from the compartment 27^a of the conveyer into the boot of the elevator 20 of the compartment 17. This elevator delivers the ore to the 85 roasting-compartment 18 through the instrumentality of the discharge-pipe 22^a, whereby the fine ore particles are continuously worked through the furnace.

The intensely fine dust which collects in 90 the second wing 24^c of the dust-chamber falls upon the chute 24^e and thence into a compartment 27^c of the conveyer-trough 27, whence it is conveyed to the screw 43, by means of which it is delivered to the bottom 95 of the compartment 18, where it mingles with the body of the ore coming through the furnace and passes with it into the hot-ore pit 45. The fine dust contains a large proportion 100 of sulfates, which are very desirable for the decomposition of the sodium chlorid, which is added to the ore as it drops into the pit, thus releasing the necessary chlorin to chloridize the silver and other elements while the ore is in the pit.

Near the roof of the dust-chamber is a sheet-metal pipe 28, whose object is to reduce the temperature of the furnace-gases before passing them into the acid-tower and also to transfer some of the waste heat in the furnace-gases to the current of pure air inside the pipe, which air may be used for heating the buildings and supplying various combustion-chambers with heated air. The air is circulated through this pipe by a suitable fan. 115 (Not shown.) The draft in the furnace is secured by a large exhaust-blower 30, which draws the furnace-gases and forces them through the condensing or acid tower 31. The interior of this tower is filled with checker 120 brickwork 31^d. The brickwork is kept wet by a stream of water sprinkled upon the top of the brickwork from a pipe 31^e, the tower being open at the top for the purpose. The wet brick condense the metallic fumes from 125 the gases as the latter pass through and among them.

The solution will absorb some of the sulfuric and sulfurous acid from the gases, also hydrochloric acid, if the ore is given a chloridizing roasting. The furnace-gases finally pass into the atmosphere at the top of the acid-tower.

The operation of the furnace is as follows:

The ore is first crushed, so that it will pass through a twenty or thirty mesh screen, and then elevated to the top of the furnace by an elevator 21 and dropped into the middle compartment 16. Here it meets the furnace-gases and falls downward with the gases to the bottom of the shaft, where it is deflected by an inclined wall 16^a and discharged into the path of the elevator 19, which raises it to the top of the furnace and drops it into the next compartment 17. The temperature in the compartment 16 is kept just high enough—say from 400° to 600° Fahrenheit—to start the combustion of the ore particles. In fact, the theory of this furnace is to surround each individual particle with a highly-oxidizing atmosphere maintained at the necessary temperature to continue the burning of the ore particle in its passage through the furnace until the oxidization is completed. The furnace-gases pass from the first compartment 16 by way of a flue 16^c into the compartment 17, near the bottom of the furnace. The ore in falling through this compartment 17 meets the rising furnace-gases. It is necessary to maintain a higher temperature in this compartment—say from 500° to 800° Fahrenheit. Hence the function of the supplemental combustion-chamber 25. However, when the sulfur contents of the ore are high this fireplace 25 is not required, as the oxidizing of the sulfur and base metals produces ample heat. From the bottom of the compartment 17 the ore is taken by the elevator 20 and delivered to the top of the third compartment 18. In this compartment the ore is also exposed to a finishing heat, or from 1,200° to 1,400° Fahrenheit, and to a superabundance of oxygen, which is introduced fresh from the hot-air compartments. With certain ores it is desirable to introduce a small amount of producer-gas to maintain the temperature in the lower part of this compartment. This may be done by way of a pipe 34. (Shown in Fig. 1.)

The operation of the hot-air compartments is as follows: The fire in one of them being started, the flue 13, leading from one to the roasting-compartment, is closed by the damper 14, while the valve 6 at the top of the checker-work is opened. The fuel-gases from the fire then pass through and among the checker-work, bringing the brickwork up to a high temperature. When this brick checker-work has been brought to the required temperature, the fire-box doors are closed, the flue 13 opened, the valve 6 at the top closed, and the corresponding blast-gate 12 opened, so that the blast of cold air and steam from the blower 10 is forced up the pipe 19 and down through the checker-work, getting hotter and hotter in its passage through the brickwork, until it finally leaves the red-hot bricks through the flue 13 among the red-hot particles of falling ore in the roasting-compartment. While the air is passing through one of the hot-air compartments, the fire is being applied to the other, so that by alternating

every two hours a continuous stream of superheated air is introduced into the roasting-compartments.

To one side of the wall of the roasting-compartments 16, 17, and 18 is formed a brick housing 35, inclosing the vertical elevators 19, 20, and 21. The bottom of the space inclosed by this housing communicates with the roasting-compartments 16, 17, and 18 by means of openings 36, through which the ore passes from the inclined bottoms 16^a, 17^a, and 18^a of the roasting-chambers. The brick housing 35 projects above the top of the roasting-chambers or compartments to facilitate the discharge from the elevators into the top of one compartment or the other, as may be desired. In like manner a housing 37 is formed between the two wings of the dust-chamber 85 to receive the contents of the latter, which pass through openings 38 at the lower extremities of the inclined bottoms 24^a and 24^e. This housing 37 incloses the conveyer 27 and extends forward or to the left (see Figs. 1 and 2) of the dust-chamber in order to discharge into the boot of the elevator 20 and into the screw conveyer 43, as heretofore described.

Having thus described my invention, what I claim is—

1. In a stack oxidizing-furnace, the combination of two or more shaft-compartments, a dust-chamber compartment, means to elevate the hot and partially-roasted ore falling at the bottom of one of the shaft-compartments, to the top of another shaft-compartment, and means to collect the hot and partially-roasted dust falling in the dust-compartment and elevate it to the top of one of the shaft-compartments.

2. In a stack oxidizing-furnace, the combination of two or more shaft-compartments, a dust-chamber compartment, a vertical elevator extending from the bottom of one compartment to the top of the next compartment, and a horizontal conveyer to collect the dust in the dust-compartment and convey it to the vertical elevator.

3. In a stack oxidizing-furnace, the combination of two or more shaft-compartments, a dust-chamber compartment, an elevator located outside the wall of said compartments, and extending upwardly to the top thereof, and an opening at the bottom of one compartment to allow the ore to pass therefrom to the elevator for the purpose set forth.

4. In a stack oxidizing-furnace, the combination of two or more shaft-compartments, a dust-chamber compartment, an elevator to convey the ore from the bottom of one compartment to the top of another compartment, and means to distribute and scatter the ore at the top of the compartment to which it is elevated.

5. In a stack oxidizing-furnace, the combination of two or more shaft-compartments, a dust-chamber compartment, means to elevate the hot and partially-roasted ore falling at the bottom of one of the shaft-compartments,

to the top of another shaft-compartment, and means to collect the hot and partially-roasted dust falling in the dust-compartment and elevate it to the top of one of the shaft-compartments, and means to distribute and scatter the ore at the top of the shaft-compartments.

6. In a stack oxidizing-furnace, the combination of two or more vertical ore-roasting compartments, an elevator connecting the bottom of one to the top of another, an air-heating compartment, a combustion-chamber communicating with the air-heating compartment, a flue connecting the air-heating compartment with the ore-roasting compartment, a damper to open and close said flue, and a valve at the end of the heating-compartment opposite the combustion-chamber.

7. In an oxidizing-furnace, the combination

of a roasting-compartment, a dust-chamber 20 consisting of two sections, means for returning the dust from one section to the roasting-compartment, and means to deliver the dust from the other section to the hot roasted ore coming from the roasting-compartment. 25

8. In an oxidizing-furnace, the combination of a roasting-compartment, a dust-chamber compartment, means for delivering the dust from the dust-chamber compartment and mingling it with the hot ore from the roasting-compartment, and a pit to receive and store the hot ore mixed with the fine dust. 30

In testimony whereof I affix my signature in presence of two witnesses.

JOHN E. GREENAWALT.
